A. JENSEN.

HEATER.

APPLICATION FILED MAR. 31, 1911. RENEWED JUNE 10, 1913.

1,080,454.

Patented Dec. 2, 1913.

J. C. Friedner
773. Keating.

UNITED STATES PATENT OFFICE.

AAGE JENSEN, OF OAKLAND, CALIFORNIA.

HEATER.

1,080,454.

Specification of Letters Patent.

Patented Dec. 2, 1913.

Application filed March 21, 1911, Serial No. 615,952. Renewed June 10, 1913. Serial No. 772,914.

To all whom it may concern:

Be it known that I, AAGE JENSEN, a citizen of the United States, residing at Oakland, in the county of Alameda and State of California, have invented new and useful Improvements in Heaters, of which the following is a specification.

The present invention relates to an improved machine for heating liquids such as 10 milk and cream.

The object of the invention is to provide a machine of this character which, while maintaining the liquid entirely separate from outside air, will act as a pump to automatically supply itself with liquid from a suitable source of supply, to cause the liquid to flow through the machine, and to raise the liquid to a higher level for convenience in further treatment, and which can easily be 20 taken apart and the wearing surfaces properly located and adjusted.

In the accompanying drawing, the figure is a vertical section of my improved machine, certain parts being shown in side 25 elevation.

Referring to the drawing, 87 indicates an outer cylindrical wall supported upon standards 2, and 86 indicates an inner cylindrical wall, said walls being connected at 30 their ends with casing heads 91, 88, and thus forming a water jacket. Into the space between these walls hot water is supplied from a vessel 120, having an overflow pipe 121, by a pipe 122, which connects with a 35 T-fitting 123, which latter connects with a pipe 124, into which the water is driven by the impact of steam emerging from a nozzle 125. From the pipe 124 the hot water flows into an annular pipe 95 between said inner 40 and outer cylindrical walls 86, 87, flowing therefrom by minute holes 96 into said water jacket. From said jacket it flows through holes 97 into an annular pipe 98, which pipe connects with a pipe 126, connecting 45 with the pipe 122. Circulation is thus maintained through said jacket.

The liquid to be treated is drawn in by 50 an inlet opening 92, which leads centrally through the casing head 91. In the other casing head 88 is formed the outlet conduit 89, connected with a pipe 61, into which is inserted a thermometer 60. In a suitable bearing in said head 88 is mounted a shaft 127, having thereon tight and loose pulleys 55 128, 129. The inner end of said shaft is screwed, as shown at 30, into one head of a

drum 83, the other head 84 rotating upon a stud shaft 31 projecting inwardly from the head 91. Said head 84 is provided with impeller vanes 85, which, in the rotary motion 60 of the drum, tend to draw liquid through the inlet 92 and propel it along the narrow annular space between the drum 83 and the inner wall 86 and out by the outlet 89. A washer 41 surrounds the shaft 127, and, 65 pressing against said washer, is a collar 42 on said shaft, making a tight joint thereat. Ball bearings 43 are interposed between stationary and movable parts around said shaft.

I claim:—

1. In an apparatus of the character described, the combination of a cylinder having closed ends, means for maintaining a circulation of water around said cylinder, a drum within said cylinder also having closed 70 ends and a cylindrical wall closely adjacent to the inner wall of the cylinder, means connected to said drum and passing through one end of the cylinder for transmitting rotary movement to said drum, said cylinder having an inlet at the center of one end thereof, and the end of the drum adjacent to said latter end having thereon impeller vanes for impelling liquid to cause it to pass between said drum and cylinder wall, the other 75 end of the cylinder being provided with an upwardly directed outlet conduit.

2. In an apparatus of the character described, the combination of a cylinder having closed ends, means for maintaining a circulation of water around said cylinder, a drum within said cylinder also having closed 80 ends and a cylindrical wall closely adjacent to the inner wall of the cylinder, means connected to said drum and passing through one end of the cylinder for transmitting 85 rotary movement to said drum, one end of said cylinder being removable and formed with an inlet opening, and provided with means for rotatably and removably supporting the corresponding end of the drum thereon, the other end of the cylinder being provided with an outlet conduit, one end of the drum being provided with impeller vanes causing the liquid to pass between the drum 90 and the inner wall of the cylinder.

3. In an apparatus of the character described, the combination of a cylinder having closed ends, means for maintaining a circulation of water around said cylinder, a drum within said cylinder also having closed 95 ends and a cylindrical wall closely adjacent 100 to the inner wall of the cylinder,

to the inner wall of the cylinder, means connected to said drum and passing through one end of the cylinder for transmitting rotary movement to said drum, one end of the cylinder being removable and having a central inlet conduit, and formed on its inner side with centrally located means for removably and rotatably supporting the corresponding end of the drum, said end being 10 provided with impeller vanes for impelling

the liquid, to the other end of the cylinder, said cylinder being formed with an outlet conduit at said other end.

In testimony whereof I have hereunto set my hand in the presence of two subscribing 15 witnesses.

AAGE JENSEN.
